UNITED STATES PATENT OFFICE.

HENRY H. KRYGER, OF MINNEAPOLIS, MINNESOTA, ASSIGNOR OF ONE-HALF
TO THOMAS J. CANNEY, OF SAME PLACE.

APPARATUS FOR REMOVING SNOW FROM RAILWAY-TRACKS.

SPECIFICATION forming part of Letters Patent No. 426,130, dated April 22, 1890.

Application filed February 25, 1889. Serial No. 301,108. (No model.).

To all whom it may concern:

Be it known that I, HENRY H. KRYGER, of Minneapolis, in the county of Hennepin and State of Minnesota, have invented certain Improvements in Apparatus for Removing Snow from Railway-Tracks, of which the following is a specification.

The object of this invention is to provide an improved apparatus for cutting through snow-drifts upon railway-tracks, and also for clearing the snow from spaces between the rails of the tracks.

The present invention is an improvement upon the inventions for which I have already made applications for Letters Patent, Serial No. 295,072, filed December 31, 1888, and Serial No. 297,874, filed January 28, 1889.

In the accompanying drawings, forming part of this specification, Figure 1 is a side elevation and partial section of my improved apparatus. Fig. 2 is a transverse vertical section of the same. Fig. 3 is the bottom of a portion of the elevator, showing the means for moving the same. Fig. 4 is a plan view 25 of the fan, partially broken away to show the arrangement of the cut-off device. Figs. 5 and 6 are details. Fig. 7 is a detail showing means for reversing the movement of the fan.

In the drawings, 2 represents a suitable car upon which the apparatus is mounted. The forward end of the car is preferably open, while the rear portion thereof is provided with a suitable structure 3, within which the driving apparatus, hereinafter described, is preferably located. A lookout-box 5, provided with windows, may, if preferred, be located upon the top of the structure 3. At the forward end of the car I arrange an elevator-frame 7, provided with the shafts 8 and 9, 40 from which passes the elevator 10, which is provided with the knives 11 and carriers 12, substantially as in my last application hereinbefore referred to.

Standards 13 are arranged at the forward 45 end of the car, and in these standards is mounted a transverse shaft 14. Blocks 15 are secured upon these shafts and are arranged in guides 16 upon the elevator-frame 7. The shaft 14 is also provided with suitable pinions 17, which engage rack-bars 18

upon the under surface of the elevator-frame. Brace-rods 19 are pivoted to the upper portions of the elevator-frame and are provided with threaded ends, which pass through the threaded hand-wheels 21. These hand-wheels 55 rest upon blocks 22, that are pivoted to the upper ends of the fixed standards 23. By rotating the shaft 14 the elevator-frame may be raised or lowered, and by turning the hand-wheels 21 the inclination of the elevator-frame may be changed. By this means the upper end of the frame may be brought below the fan-casing, hereinafter described.

Arranged upon the top of the structure 3, at the forward portion thereof, is a horizontal fan-casing 24, which is open at its center, and upon the top of which is located a hopper 25, which is adapted to receive snow from the elevator and direct it into the fan-casing. The fan-casing is preferably provided with 65 the oppositely-projecting discharge-spouts 26. A movable cut-off plate 27 is provided, which is adapted to close either of said spouts 26. This plate is provided with a rack-bar 28, engaged by a pinion 29 upon the shaft 30. This 70 shaft projects into the interior of the structure 3 and is provided with a hand-wheel, by means of which it may be operated.

A shaft 31 is mounted in bearings upon the car, preferably within the structure 3, and extends upward into the fan-casing, where it is provided with a suitable fan 32. A cone-shaped plate 33 is preferably secured to the central part of the fan, and serves to direct the snow which falls into the hopper to the 85 outer part of the fan-casing.

I arrange upon the car 2, preferably within the inclosed portion 3, a suitable engine 35. This engine is preferably of the horizontal-cylinder type, and it is preferably connected 90 directly to the main shaft 36. This shaft is provided with a gear-wheel 37, which engages a similar gear 39 upon the shaft 38. The shaft 38 is also provided with the beveled gears 41, either one of which is adapted to engage a 95 beveled pinion 42 upon the fan-shaft 31. The gears 41 are splined upon the shaft and are adapted to be moved by suitable levers. By this means the fan may be rotated in either direction, and the snow which is deposited in 100

the hopper by the elevator may be discharged at either side of the track. The shaft 38 is also preferably provided with the sprocket-wheels 43, from which, by means of chains 44, 5 the elevator may be operated. A shaft 45 is preferably arranged at the forward end of the car, and is provided with the cutter-wheels 46, which are arranged to clear the ice from the top of the rails and also to cut a channel 10 inside of the rails. These wheels are substantially the same as those described in my last-named application hereinbefore referred to.

For the purpose of removing the snow from 15 the space between the track-rails, I provide a cutter-cylinder 47, mounted upon a vertically-movable frame 48 and driven by belts 49 and 50 from the driving-shaft 36. The construction and arrangement of this cylinder are preferably substantially the same as in my said 20 former application.

For the purpose of raising and lowering the frame 48, I prefer to provide an air-cylinder 51, having the piston 52 fitting therein and 25 connected to the frame 48. Air may be supplied to this cylinder by means of the pipe 53 from the engine, or it may be exhausted therefrom, and thereby the frame or cylinder will be lowered or raised.

30 Secured beneath the car in the rear of the cylinder 47 is a box 54, having an open front. A plate 55 has its rear edge pivoted to the forward edge of the box 54, and its forward edge is beveled to arms 56, that are connected 35 with the shaft of the cylinder. At each end of the box 54 is a fan-casing 59, having an open center connecting with the box 54. Each of said casings is also provided with a discharge-spout 60, which extends upward by the 40 side of the car and has an open end arranged near the top of the car. A shaft 61 is provided with fans 62, which are arranged in the casings 59. This shaft is also preferably provided with a pulley 63, which is adapted to be 45 driven by the belt 64 from the main shaft 36.

The frame 48 is preferably provided at its upper end with a shaft 65, having a pulley 66, which is driven by the belt 50, and with pulleys 67, over which the belts 49 pass. I 50 may provide the frame 48 with movable frames 68, in which the shaft 65 is mounted. These frames are made vertically movable, and are provided with threaded rods 69 and hand-wheels 70, by means of which the frame 68 55 may be vertically adjusted for the purpose of tightening the belts 49.

In some instances I prefer to construct the knives 11 as shown in Fig. 5. As here shown, the knives are of rectangular form, open at 60 both front and rear, and secured at their centers to the elevator-chains. Any preferred number of these knives may be used.

I may also arrange upon the car a head-light 74, secured upon a bar 71, which is provided with a pinion 72, that meshes with a 65 fixed rack-bar 73. The light 74 may be raised,

so as to light the track over the top of the elevator, or it may be lowered when necessary for it to pass under a bridge.

The operation of the apparatus will be 70 readily understood from the foregoing detailed description.

In running over the road where there are no drifts the elevator and its fan may be disconnected from the driving-shaft, so that they 75 will not be operated. The cylinder 47 may then be operated alone, and it will cut up the snow in the space between the rails and deposit it in the box 54. It will be drawn out of this box by fans 62 and discharged through 80 the spouts 60. When the elevator is in use, the snow carried up by it will be deposited in the hopper and passed into the fan-casing, and will then be deposited at one side of the track by means of the horizontal fan. 85 The fan may be rotated in either direction and the snow deposited at either side of the track.

I claim as my invention—

1. The combination, with a suitable car, of 90 the inclined elevator-frame secured upon the forward end of said car, an elevator arranged upon said frame, a horizontal fan-casing arranged beneath the upper end of said elevator and provided with oppositely-extending 95 discharge-spouts, and a discharge-fan arranged in said casing and adapted to be rotated in either direction, substantially as described.

2. The combination, with a suitable car, of 100 the inclined elevator secured upon the forward end of said car, the horizontal fan-casing arranged beneath the upper end of said elevator, the hopper connecting with the open center of said casing, and the fan arranged 105 in said casing and provided with a conical plate arranged to direct the snow toward the outer portion of said casing.

3. The combination, with a suitable car and the inclined elevator arranged at the forward portion thereof, of the fan-casing adapted 110 to receive material from said elevator and provided with the discharge-spouts 26, the movable cut-off plate 27, arranged to close either of said spouts, and the fan 32, adapted 115 to be driven in either direction, substantially as described.

4. The combination, in an apparatus of the class described, with a suitable car 2, and with a structure 3, inclosing the driving mechanism, of the inclined elevator secured upon the forward end of said car, the horizontal fan-casing arranged beneath the upper end of 120 said elevator and upon the top of said structure 3, and the fan arranged in said casing and provided with a vertical shaft 31, arranged to be driven by mechanism located within said structure 3, substantially as described.

5. The combination, with the car, of the movable elevator-frame provided with the 125 guides 16 and the rack-bars 18, the shaft 14, mounted upon said car and provided with

the blocks 15, arranged in said guides 16, and the gear-wheels 17, engaging said rack-bars 18, substantially as described.

6. The combination, with the car and the cutter-cylinder 47, arranged to clear the space between the rails, of the open box 54, arranged in the rear of said cylinder, the fan-casings at the opposite ends of said box, provided with the discharge-spouts 60, and the

fans arranged in said casings, substantially 10 as described.

In testimony whereof I have hereunto set my hand this 20th day of February, 1889.

HENRY H. KRYGER.

In presence of—

A. C. PAUL,
A. M. GASKILL.
